SELF-REGULATING SPRINKLER

Orton H. Englehart, Glendora, Calif.

Application July 31, 1940, Serial No. 348,672

7 Claims. (Cl. 299—69)

My invention relates to water sprinklers of the rotating jet type and has for its principal objects to provide a sprinkler which in service will act automatically to discharge a predetermined quantity of water regardless of the pressure prevailing in the supply line to which the sprinkler is connected and further, to provide simple and efficient means for minimizing leakage through the joint or bearing between the rotating body of the sprinkler and the supply pipe on which said body is mounted.

Where a number of sprinklers are served by a single supply pipe, there is usually considerable variation of the volume of water discharged from the different sprinklers due to differences in elevation or unequal pressures due to friction between the rotary sprinkler and the supply pipe.

Such variable discharge is very undesirable inasmuch as considerable water is wasted where the sprinkler discharges more water than is necessary and further, the excessive amount of water discharged from the sprinkler frequently damages the plant growth and crops.

While it is possible to manually regulate each sprinkler by means of some form of valve, such practice will involve considerable time, labor and consequent expense, particularly where a portable sprinkling system is used and which requires individual adjustment of each sprinkler after each move of the portable system.

With the foregoing and other objects in view, my invention consists in certain novel features of construction and arrangement of parts that will be hereinafter more fully described and claimed and illustrated in the accompanying drawing in which:

Fig. 1 is a side elevational view partly in section of one form of my improved sprinkler.

Fig. 2 is a horizontal section taken on the line 2—2 of Fig. 1.

Fig. 3 is a vertical section taken through the center of the form of sprinkler illustrated in Fig. 1 and showing the rotary head in elevated position.

Fig. 4 is a vertical section taken through the center of a modified form of the sprinkler.

In the form of sprinkler illustrated in Figs. 1, 2, and 3, 10 designates an upright pipe that is connected to a source of water supply under pressure and mounted to rotate freely on the upper portion of said pipe is a head H containing in its upper portion a chamber 12 and communicating with said chamber are the inner ends of tubular arms 13, the outer end portions of

which are slightly inclined and carry jet nozzles 14.

Head H is mounted on the upper portion of a sleeve 11 and the latter is mounted to rotate freely and slide vertically on tubular spindle 10.

As a result of the construction just described, rotation of the head H is accomplished by reaction of the jets of water issuing from the nozzles 14.

10 Removably positioned in the upper end of the tube 10 is a screw plug 15 provided on its upper end with a flange 16 that projects beyond the periphery of tube 10, thereby providing a stop against which the top of sleeve 11 which forms 15 the bottom surface of the chamber 12 engages to limit the upward movement of rotary head H and sleeve 11.

Formed through the wall of tube 10 immediately below plug 15 is an aperture 17. Seated 20 in the top of head H and extending downwardly into the upper portion of chamber 12 is a screw 18, the lower end of which is adapted to engage on top of screw plug 15, thereby limiting the downward movement of rotary head H on 25 tube 10.

Since a portion of the bottom surface of chamber 12 is displaced by the tubular spindle 10 on which the head H rotates, the water pressure has greater effect on the top surface of the chamber 30 12 than on its bottom surface and as a result there is an upward thrust on the rotary head while the sprinkler is in operation.

When the sprinkler is placed in service and the pressure within chamber 12 is sufficient to 35 lift the weight of rotary head H and parts carried thereby, said head will move upward with the result that the sleeve 11 will pass upwardly to partially close aperture 17, consequently reducing the pressure within chamber 12 so as to 40 establish an equilibrium which maintains a constant pressure and consequent uniform discharge of water through the rotary head and from the jet nozzles 14.

The pressure at which equilibrium is established depends upon the relation of the weight of the sprinkler head to the area displaced by the spindle that enters chamber 12.

Screw 18 is provided as a pivot to carry the weight of the sprinkler head and allow rotation 50 thereof at line pressure below the equilibrium point.

The projecting marginal portion of flange 16 prevents the rotary head from becoming inadvertently detached from the tube 10 while the 55 parts of the sprinkling system are being handled.

Formed in the sleeve 11 a substantial distance below the chamber 12 is an annular groove 19 that communicates with the bearing formed through the head for tube 10 and leading from the bottom of chamber 12 downwardly through the head and communicating with groove 19 is a passage 20.

Such construction prevents the pressure below the annular groove in the clearance between the tube 10 and head H from becoming greater than the pressure prevailing in chamber 12 and thus excessive leakage through the bearing between the tube and head is prevented. Otherwise, the full line pressure from partially closed ports would be exerted to produce leakage which might be considerable at relatively high pressure.

The pressure in the clearance above the groove 19 may be equal to the line pressure, but the groove and duct relieve that pressure by carrying the leakage due to pressure difference, back to chamber 12.

This particular form of sprinkler is particularly adapted to operate at relatively low pressures and to construct the same so that it would operate at a relatively high equilibrium point would necessarily add considerable extra weight which would be unwieldy and cumbersome.

The modification illustrated in Fig. 4 enables the normal weight to be maintained and at the same time establish practically any desired equilibrium point by varying the ratio of the diameter of tubular spindle 10a to the diameter of an axially arranged stem 10b that projects from the upper end of spindle 10a upwardly through a bearing in the top of the rotary sprinkler head 11a, the diameter of said stem always being smaller than the diameter of the tubular spindle. In this construction, the equilibrium point is reached when the difference in cross sectional area between the spindle 10a and stem or extension 10b, times the unit pressure, equals the weight of the sprinkler head unit.

The modified construction illustrated in Figs. 5, 6, and 7 is particularly adapted for the types of sprinklers that are caused to rotate as a result of successive impacts of an oscillating arm and which form of sprinkler is disclosed in my above mentioned issued patent.

In this construction, sprinkler head unit 40 is mounted on the upper end of a tubular spindle 41 that is caused to rise through the upper portion of a head 41a that is mounted on the upper end of an upright supply pipe 41b. As the spindle 41 moves upward, the passage of water from chamber 52 in the upper portion of head 41a through port 43 into spindle 41 is restricted. This rise and corresponding restriction of water flow into the spindle continues until the pressure in chamber 42 that is formed in the lower portion of head 41a exerts an upward thrust on spindle 41 that equals the weight of the sprinkler head unit 40 plus the pull of a spring 44 that is located in chamber 42.

The tension of this spring may be adjusted by a screw 45 that is seated in a plug 45a that closes the lower end of chamber 42, thus establishing a balance or equilibrium point at the desired pressure. The swivel joint 44a at the upper end of spring 44 allows tubular spindle 41 to rotate while the spring 44 remains stationary. Ports 46 formed in the lower end of the tubular spindle 41 enables pressure within said spindle to prevail in chamber 42.

In this construction, the tubular spindle 41 may be provided with an annular groove 47 that cor-

responds with the groove 19 in the form of sprinkler illustrated in Fig. 1 and with a duct leading from said groove so as to prevent excessive leakage through the joint between the tubular spindle and head 41a.

Inasmuch as this form of sprinkler is rotated as the result of impacts of an oscillating arm A that is mounted on top of the head 40 and which is actuated by the jet of water issuing from jet 10 nozzle N that projects from head 40, it is necessary to provide for considerable friction between the rotating head 40 and the head or body member 41a that is mounted on tubular supply pipe 41b. Otherwise, the impacts resulting from the 15 oscillation of arm A would cause head 40 to rotate or move back and forth through a relatively small arc instead of moving intermittently through a complete circle.

To provide this necessary friction, a collar 48 20 of resilient metal having a projecting finger 49 is mounted on the upper portion of fixed head 41a and secured to and depending from the rotary head 40 is a yoke 51 that receives finger 49.

This construction enables the head 40 mounted 25 on the upper end of tubular spindle 41 to move vertically which is necessary in order to permit the regulating means to function and at the same time such structure provides the necessary frictional resistance to rotary motion of head 40 and 30 the nozzle or nozzles carried thereby.

Thus it will be seen that I have provided a self-regulating sprinkler that is relatively simple in construction, inexpensive of manufacture and very effective in performing the functions for 35 which it is intended.

It will be understood that minor changes in the size, form and construction of the various parts of my improved self-regulating sprinkler, may be made and substituted for those herein shown 40 and described, without departing from the spirit of my invention, the scope of which is set forth in the appended claims.

I claim as my invention:

1. In a water sprinkler, a tubular spindle, a 45 sleeve mounted for rotation thereon, a head connected to said sleeve and containing a chamber, a groove formed in said sleeve which communicates with the bearing space between the spindle and the sleeve, and a passage formed in said 50 sleeve which connects said chamber and said groove, said passage being independent of the space between the said spindle and the said sleeve.

2. In a water sprinkler, a tubular spindle, a 55 sleeve mounted to rotate and slide upon said spindle, a head connected to said sleeve and containing a chamber, an outlet from said chamber, said spindle having an opening that communicates with the said chamber and means inde- 60 pendent of the space between the said spindle and the said sleeve for conducting the leakage pressure from the space between said spindle and said sleeve into the said chamber.

3. A water sprinkler as set forth in claim 2 65 and with means for limiting the upward movement of the sleeve on said tubular spindle.

4. A water sprinkler as set forth in claim 2, with the surface of the bearing in said sleeve being in direct contact with the surface of said 70 spindle so that the effective size of the said opening is diminished as the sleeve and sprinkler head moves upward on said tubular spindle.

5. In a water sprinkler, a tubular spindle, a 75 sleeve mounted to rotate and slide upon said spindle, a head connected to said sleeve and con-

taining a chamber having an outlet therefrom, there being an opening formed in said spindle with the surface of the bearing in said sleeve in direct contact with the surface of said spindle so that the effective area of said opening is diminished as the sleeve moves upward on said spindle, means for conducting the leakage pressure from the space between said sleeve and spindle into the chamber in said head and a stem projecting from the upper end of said spindle through the upper portion of said head, the diameter of which stem is less than the diameter of said spindle.

6. In a water sprinkler, a tubular spindle, a sleeve mounted to rotate and slide upon said spindle, a head connected to said sleeve, said head containing a chamber having an outlet therefrom, there being an opening formed in said spindle at a point where it is open when the sleeve is at the lower end of its travel, the effective area of which opening is diminished as the sleeve moves upward on said spindle and a stem projecting from the upper end of said spindle through the upper portion of said head, the diameter

of which stem is less than the diameter of said spindle so as to maintain a relatively constant pressure in the chamber within the head as a result of the water pressure lifting said sleeve to restrict the effective size of the opening in the tubular spindle until a balance is established between the combined weight of said sleeve and sprinkler head and the upward thrust exerted by liquid pressure in the head.

- 5 7. In a water sprinkler, a tubular spindle, a sleeve mounted to rotate and slide upon said spindle, a head connected to said sleeve and containing a chamber having an outlet therefrom, the duct through said spindle communicating with said chamber, there being an elongated bearing between said sleeve and spindle, said sleeve being provided at the intermediate portion of said elongated bearing with a groove and there being a duct formed in said sleeve for establishing communication between said groove and the chamber in said head.
